UNITED STATES PATENT OFFICE.

EDWIN J. SIBLEY, OF WESTBURY, NEW YORK.

DESIGN FOR A COMBINED SHUTTER HOOK AND SPRING.

Application filed November 11, 1926. Serial No. 19,680. Term of patent 3½ years.

To all whom it may concern:

Be it known that I, EDWIN J. SIBLEY, a citizen of the United States, and resident of Westbury, in the county of Nassau and State of New York, have invented a new, original, and ornamental Design for a Combined Shutter Hook and Spring, of which the following is a specification, reference being had to the accompanying drawing, forming part thereof.

The figure is a perspective view of a combined shutter hook and spring, showing my new design.

I claim:

The ornamental design for a combined shutter hook and spring, as shown.

EDWIN J. SIBLEY.
